Attorney

UNITED STATES PATENT OFFICE.

JEFF M. BLAIR, OF HUMBLE, TEXAS.

LINK.

Application filed June 13, 1924. Serial No. 719,870.

To all whom it may concern:

Be it known that I, JEFF M. BLAIR, a citizen of the United States, residing at Humble, in the county of Harris and State 5 of Texas, have invented certain new and useful Improvements in a Link, of which the following is a specification.

This invention relates to new and useful improvements in links which are principally adapted for use in connection with traveling blocks which are provided with a hook, the blocks being principally used in oil fields.

One of the important objects of the present invention is to provide a link of the above mentioned character, which will save considerable time and labor in changing from a hook to a swivel connection such as is commonly done in connection with the implements used in drilling oil.

20 A further object of the present invention is to provide a link of the above mentioned character, wherein locking means is provided for closing the open portion of the link after the hook or swivel has been suspended therein, means being further provided for preventing the locking means from automatically or accidentally becoming unlocked.

25 A still further object of the invention is to provide a link of the above mentioned character, which is simple in construction, inexpensive, strong and durable and furthermore adapted for the purposes for which it is designated.

30 Other objects and advantages of this invention will become apparent during the course of the following description.

In the accompanying drawing forming 40 part of this specification and in which like numerals designate like parts throughout the same:

Figure 1 is a side elevation of my improved link showing the same in a locked position, and

45 Figure 2 is an edge view thereof.

In the drawing wherein for the purpose of illustration is shown the preferred embodiment of my invention, the numeral 1 designates generally my link which is formed of any suitable metallic material and is preferably C-shaped in design in the manner illustrated in Figure 1. The lower free end 2 of the C-shaped link 1 is provided with a laterally extending lip 3, the purpose of which will be hereinafter more fully described. A pair of plates such as shown at

4 and 5 respectively in the drawing are pivotally supported at their upper ends to the upper free end 6 of the C-shaped link 1 on the transversely extending pin 7, the plates 4 and 5 being arranged on opposite sides of the upper free end of the link in the manner clearly illustrated in Figure 2. The lower ends of the plates 4 and 5 are adapted to extend over the lateral lip 3 on opposite sides of the lower free end 2 of the link and pivotally supported between the lower end of the plates is the latch member 8. The latch member 8 is provided with a laterally extending projection 9 on its opposite sides for operation with suitable apertures provided in the lower ends of the plates 4 and 5 in the manner clearly illustrated in Figure 2 of the drawing whereby the latch may be pivotally supported between the lower free ends of the plates. The latch member is adapted to engage the under portion of the lip 3 in the manner clearly illustrated and the lower end of the latch terminates into a handle 10 whereby the same may be actuated whenever necessary.

For the purpose of securing the latch 8 in engagement with the lip 3, I provide the plate 4 with a notch 11 in one side thereof in the manner clearly illustrated in Figure 1 of the drawing and adapted to be received in the notch 11 is the locking dog 12 which is pivoted at 13 on the lower free end 2 of the C-shaped link. The parts are arranged as is shown in Figure 1 of the drawing, the space between the free ends of the C-shaped link is closed by the plates 4 and 5 and held in this position by means of the latch 8 and the locking dog 12. Whenever it is desired to remove either the hook or swivel which is adapted to be supported by the link 1, the locking dog 12 is swung on its pivot 13 out of engagement with the notch 11 and by raising upwardly on the handle 10, the latch may be disengaged from the under side of the lip 3 and the plates 4 and 5 swung upwardly on the pivot 7, thus enabling either the hook or swivel supported within the link to be removed therefrom and interchanged as the case may be. It is also to be understood that should the link be sprung, this action will cause the latch to be further held in engagement with the lip 3 thus securely locking the plates in their extending position.

The simplicity of my device enables the same to be manufactured at a very low cost

and will further be strong and durable. Furthermore, the parts are so arranged as to be readily actuated and will save considerable time and labor in changing from 5 a hook to a swivel in a manner which is well known in the art of oil drilling.

While I have shown the preferred embodiment of my invention, it is to be understood that various changes in the size, shape and 10 arrangement of parts may be resorted to without departing from the spirit of the invention and the scope of the appended claim.

Having thus described my invention, what 15 I claim is:—

A hook structure comprising a link having spaced ends and provided at one end

with an outstanding lip, and provided at its outer side and under the lip with a recess, link plates pivotally connected with the opposite end portion of the link and adapted to bridge the space between the end portions and overlap the recess, a latch member pivotally mounted between the free ends of the link plates and adapted to engage under the lip and enter the recess, one of the link plates being provided at its edge with a notch and a locking dog pivotally mounted upon the body and engageable in the notch of the link plate. 20 25 30

In testimony whereof I affix my signature.

JEFF M. BLAIR.
